US0D1084912S

(12) **United States Design Patent** (10) **Patent No.:** **US D1,084,912 S**
(45) **Date of Patent:** **** Jul. 22, 2025**

(54) **BALANCE VEHICLE**

(71) Applicant: **ZHEJIANG CHIC ROBOT TECHNOLOGY CO., LTD.**, Jinhua (CN)

(72) Inventor: **Yijun Liu**, Jinhua (CN)

(73) Assignee: **ZHEJIANG CHIC ROBOT TECHNOLOGY CO., LTD.**, Jinhua (CN)

(**) Term: **15 Years**

(21) Appl. No.: **29/947,317**

(22) Filed: **Jun. 14, 2024**

Related U.S. Application Data

(63) Continuation of application No. 29/824,966, filed on Jan. 28, 2022, now Pat. No. Des. 1,060,123.

(30) **Foreign Application Priority Data**

Aug. 5, 2021 (CN) 202130504756.0
Sep. 28, 2021 (CN) 202130643670.6

(51) **LOC (15) Cl.** **12-07**
(52) **U.S. Cl.**

USPC **D12/1**

(58) **Field of Classification Search**

USPC D12/1, 16, 190, 101, 5, 107; D21/419,
D21/421, 423, 426, 662, 760, 763, 765,
D21/766, 769, 771, 776, 803

CPC B62K 3/007; B62K 17/00

See application file for complete search history.

(57) **CLAIM**

The ornamental design for a balance vehicle as shown and described.

DESCRIPTION

FIG. 1 is a rear, left, and top perspective view of a balance vehicle, showing my new design;
FIG. 2 is a front, left, and top perspective view of FIG. 1;
FIG. 3 is a front view of FIG. 1;
FIG. 4 is a rear view of FIG. 1;
FIG. 5 is a left side view of FIG. 1;
FIG. 6 is a right side view of FIG. 1;
FIG. 7 is a top view of FIG. 1; and,
FIG. 8 is a bottom view of FIG. 1.

1 Claim, 7 Drawing Sheets
